Primary Examiner — Lakiya Rogers*Assistant Examiner* — Altaira Swangin(74) *Attorney, Agent, or Firm* — Wood Herron & Evans LLP(57) **CLAIM**

The ornamental design for a fender vent, as shown and described.

DESCRIPTION

FIG. 1 is a front right perspective view of a fender vent according to the present invention.

FIG. 2 is a rear left perspective view of the fender vent shown in FIG. 1.

FIG. 3 is a front view thereof.

FIG. 4 is a rear view thereof.

FIG. 5 is a left side view thereof.

FIG. 6 is a right side view thereof.

FIG. 7 is a top view thereof; and,

FIG. 8 shows the fender vent of the present invention mounted on the side of a vehicle, with the rest of the vehicle shown in de-emphasized and half-tone portions so as to illustrate environmental structure. These portions form no part of the claimed invention. The broken lines shown indicate a boundary line between the claim and unclaimed environment and form no part of the claimed design.
